W. S. GOODING.

COMPOUND TOOL REST AND HOLDER FOR LATHES.

APPLICATION FILED MAR. 15, 1920.

1,383,299.

Patented July 5, 1921.

William S. Gooding,
inventor

By Charles Turner Browne,
Atty.

UNITED STATES PATENT OFFICE.

WILLIAM S. GOODING, OF CHICAGO, ILLINOIS.

COMPOUND TOOL REST AND HOLDER FOR LATHES.

1,383,299.

Specification of Letters Patent.

Patented July 5, 1921.

Application filed March 15, 1920. Serial No. 365,987.

To all whom it may concern:

Be it known that I, WILLIAM S. GOODING, a citizen of the United States, and a resident of Chicago, in the county of Cook and State 5 of Illinois, have invented certain new and useful Improvements in a Compound Tool Rest and Holder for Lathes, of which the following, reference being had to the drawing accompanying and forming a part hereof, is a specification.

This invention relates to tool rests for lathes.

Among the objects of the invention are to obtain a compound tool rest which may also 15 be used as a tool holder, attachable to plain tool rests on lathes; to obtain a compound tool rest and holder which is easily mounted and adjusted on an ordinary plain tool rest, and by means of which the same results can 20 be effectively obtained as on lathes which are provided with the well known compound tool rest. Additional objects are to obtain a compound tool rest which is durable, not liable to break or get out of order, and 25 economically made, and which is adapted for use in comparatively heavy work.

In the drawings referred to,

Figure 1 is a side elevation of a compound tool rest and holder embodying the invention.

Fig. 2 is a top plan view of the shell or case of the device, with the ends shown in horizontal section.

Fig. 3 is a view of a screw member; and 35 Fig. 4 a view of an adjustable member of the device adapted to hold a tool, and

Fig. 5 is a vertical section on line 5—5 of Fig. 4, viewed in the direction indicated by arrows.

40 Fig. 6 is a vertical section of a member secured in the right hand end of the barrel illustrated in Fig. 2, and

Fig. 7 is a front elevation of said member.

A reference character applied to designate a given part indicates said part throughout the several figures of the drawing, wherever the same appears.

50 A represents a cylindrical shell which is provided with internal screw threads, α , at one end thereof, with the parallel abutments B, B', between the ends, and with the bored out portion, α' , at the end thereof opposite to the end which is provided with screw threads α . C represents an internal abutment in shell A, which extends inward toward the axis of the shell. D represents a

tool holder and rest, which is provided with the barrel E, corresponding to and longitudinally movable in the bored out end of shell A; and F represents the head of the tool holder or rest. f , f , represent apertures in head F, which are respectively adapted to receive one end of a tool, (as X, Fig. 1), to be held thereby. Barrel E is provided with an internally screw threaded well, (G, Fig. 65 4). g , (Figs. 4 and 5), represents a longitudinally extending groove on barrel E, which corresponds with and slides easily on abutment C, to prevent rotation of member D in shell A, while permitting longitudinal 70 movement thereof in said shell. H represents a member illustrated as provided with external screw threads h corresponding with and fitting into the internal screw threads a of shell A, by means whereof said member 75 is rigidly secured in one end of said shell. I represents a screw threaded member which is rotatably mounted in member H, which extends through said member H and axially into said shell A. The screw threads on 80 member I correspond with the internal screw threads in well G, and by rotating said member I the member D is moved longitudinally in shell A. J represents an annular shoulder on member I which abuts against the adjacent end of member H. K represents an internally screw threaded head, and L represents a handle which is rigidly secured on member I, by means of said head, (or nut). The hub l of handle L is provided with internal screw threads which correspond with the external screw threads i on member I, 90 and said handle L is thereby rigidly secured on said member, to prevent longitudinal movement thereof. Head K acts as a set nut 95 on said hub l .

To assemble the several parts of the device the barrel E is inserted in the bored out end α' of shell A, with abutment C in groove g . Member D when the barrel E thereof is thus 100 inserted in the shell is movable longitudinally, but is not rotatable. Member H is secured to the opposite end of shell A, as by screw threads h and a being engaged; and the screw threaded member I is turned 105 (member H acting as the journal bearing therefor), the member D being at the same time forced inward against the said member I, and said screw threads on member I thereby engage screw threads g in barrel E. 110 Thereafter turning of handle L moves member D longitudinally in shell A.

Y represents a tool post of a plain tool rest; and to mount the device on a lathe, the abutments B, B' are moved horizontally to inclose said tool post. The bar Z is then placed in the ordinary rectangular tool aperture in post Y, so as to rest on the upper or top faces of said abutments B, B', and the set screw y of post Y is forced down on said bar Z to set said bar on said abutments, 10 to hold said abutments and shell A rigidly in place.

The abutments B, B' are to be turned in a horizontal plane to an adjusted position, prior to the setting, as above recited, of the 15 set bolt or screw y, in the same manner ordinary tools are placed in the tool post and adjusted prior to forcing the bolt or screw y down thereonto.

I claim:

- 20 1. In a compound tool rest, a shell, parallel abutments on said shell, and said shell provided with a longitudinally extending passage-way therethrough, a member longitudinally movable in said passage-way, and 25 provided with an axially extending screw threaded well, a member rigidly attached to one end of said shell, a screw threaded mem-

ber rotatably mounted in said last member, said screw threaded member corresponding with the screw threads in said well, and engageable therewith, and means to manually rotate said screw threaded member, all combined as set forth. 30

2. In a compound tool rest and holder, a shell, parallel abutments on said shell and 35 said shell provided with a longitudinally extending passage-way therethrough, a member in said passage-way, means to prevent rotation of said member, a head provided with apertures arranged to hold a tool on 40 said member, and said member provided with an axially extending screw threaded well, a member rigidly attached to one end of said shell, a member rotatably mounted in said rigidly attached member and provided at one end with screw threads corresponding with and fitting in the screw threads in said well, and a handle attached to the other end thereof, all combined as set forth. 45

WILLIAM S. GOODING.

In the presence of—

CHARLES TURNER BROWN,
B. S. BROWN.
